UNITED STATES PATENT OFFICE.

ARTHUR J. LUDWIG, OF BAXTER, IOWA.

COIN-OPERATED MECHANISM FOR GASOLENE-VENDING MACHINES AND THE LIKE.

1,378,590.

Specification of Letters Patent.

Patented May 17, 1921.

Application filed March 24, 1920. Serial No. 368,445.

To all whom it may concern:

Be it known that I, ARTHUR J. LUDWIG, a citizen of the United States, and resident of Baxter, in the county of Jasper and State of Iowa, have invented a certain new and useful Coin-Operated Mechanism for Gasoline-Vending Machines and the like, of which the following is a specification.

The object of my invention is to provide 10 a coin operated mechanism for gasoline vending machines and the like, of simple, durable and inexpensive construction.

More particularly it is the object of my invention to provide such a coin operated mechanism, including means for preventing any but the desired operation of the mechanism at any time before or after the deposit of the coin.

Still a further object is to provide such 20 a mechanism adapted to be operated upon the deposit of coins of different denominations.

Still a further object is to provide means in such a mechanism, for the return to the 25 purchaser of any smaller coin which he may have deposited in the slot designed for larger coins.

Still a further object is to provide such a mechanism adapted to be selectively used 30 with coins of different denominations, having a minimum number of simple parts.

With these and other objects in view, my invention consists in the construction, arrangement and combination of the various 35 parts of my device, whereby the objects contemplated are attained, as hereinafter more fully set forth, pointed out in my claims, and illustrated in the accompanying drawings, in which:

40 Figure 1 shows a front elevation of a machine embodying my invention.

Fig. 2 shows a vertical, transverse, sectional view through the same.

Fig. 3 shows a horizontal sectional view, 45 taken on the line 3—3 of Fig. 2.

Fig. 4 shows a detail sectional view of part of the locking mechanism.

Fig. 5 shows a side elevation of one of 50 the locking pawls and part of the mechanism for operating same.

Fig. 6 shows a vertical sectional view through the pawl illustrated in Fig. 5,

Fig. 7 shows a detail sectional view of one of the slide bars.

Fig. 8 shows a vertical sectional view illustrating one of the coin slots and the mechanism adjacent thereto.

Fig. 9 shows a detail view of part of the mechanism for operating the slide bars.

Fig. 10 shows a detail sectional view of 60 the slide bars illustrated in their relation to the locking bar.

Fig. 11 shows a detail sectional view of a portion of one of the coin slots.

Fig. 12 shows a sectional view of the block 65 in which the slide bars are mounted, with the slide bars and the locking bar installed therein.

Fig. 13 shows a detail sectional view, taken on the line 13—13 of Fig. 12, illustrating 70 one of the slide bars in certain positions of the slide bar and the locking bar; and

Fig. 14 is a similar view showing the slide bar and the locking bar in other positions of their movement.

In the accompanying drawings I have shown a casing, indicated by the reference character 10, supported on a suitable foundation 11. It is understood that the casing 10 may contain a gasoline pump or the like, 80 designed to be operated by means of a toothed bar 12 hereinafter more fully described, from a crank handle 13 on the outside of the casing 10.

Supported above the casing 10 is a casing 14, which contains the coin operated mechanism.

In the front of the casing 14 are a series of coin receiving slots 15, 16, 17 and 18. Leading from the slots just described are 90 suitable coin chutes 19, which extend inwardly and downwardly in the casing 14. The coin slots and chutes are of proper sizes to receive coins of different denominations, as, for example, dimes, quarters, half 95 dollars and dollars.

At the lower end of each coin chute 19 the chute is slightly contracted as at 20, so as to hold the coin when it has traveled a certain distance in the chute. Below the 100 contracted portion of each chute the chute is open as at 21, to permit a smaller coin than the proper one, to be discharged from said chute.

Leading from the opening 21 of each chute 19 is a chute 22 which discharges into a cup 22^a from which the purchaser may remove the coin.

5 In the upper portion of the casing 14 is mounted for rotation a transverse shaft 29. On the shaft 29 outside the casing 14 is a crank handle 30.

Fixed to the shaft 29 is a downwardly 10 extending arm 31. Pivoted to the lower end of the arm 31 is a link 32. The link 32 is pivoted to a transverse bar 33. Pivoted to the bar 33 are forwardly extending plunger rods 34, which correspond in number 15 to the number of coin receiving openings. The rods 34 are mounted in suitable bearings 35. On each rod 34 is a collar 36. Mounted on each rod 34, between the collar 36 and the bearing 35, for instance, is 20 a coil spring 37 arranged to normally hold the rod 34 at its forward limit of movement for thereby holding the shaft 29 and the crank arm 30 in starting position. Stop pins 38 limit the forward movement of the 25 plunger rods 34.

Communicating with and extending rearwardly from the lower portion of each coin chute 19 is a cylinder 39, into which from the rear end projects a rod 40. On the forward end of each rod 40 is a disk 41, adapted to travel smoothly in the cylinder 39.

Mounted on each rod 40 between the disk 41 and the closed rear end of the cylinder 39 in which such rod 40 is mounted, is a 35 coil spring 42 for normally holding each rod 40 at the forward limit of its movement.

Extending downwardly from the central portion of each cylinder 39 is a coin discharge chute 43 designed to allow coins to 40 pass freely downwardly into a coin receptacle 23 having a sight glass 24 in the front of the casing 14, and having a hinged bottom 25 fixed to a pintle 26, which is rotatably mounted. Fixed to the pintle 26 is an arm 27. Pivoted to the arm 27 is a rod 28. The rod 28 is fixed to the shaft 29, so that the rotary movement of the shaft 29 imparts swinging movement to the rod 28 and tilting movement to the hinged bottom 25. The rod 28 and arm 27 are connected together with sufficient play to permit the proper operation of the parts for tilting the bottom 25 downwardly when the crank arm 30 is operated for operating the plunger rods 34.

Suitably supported within the casing 14 is a block 44, in which are mounted the slide bars 45, 46, 47 and 48, which are connected with the respective rods 40. On the 60 under surface of the slide bars are alined notches 49 and 50. Each notch 50 has one inclined wall on the side adjacent to the notch 49, as illustrated in Fig. 7. The slide bars are arranged for fore-and-aft sliding 65 movement in the casing 14.

Pivoted to each of the slide bars is a downwardly projecting pin 52. A stop 53 limits the swinging movement of the pin 52 in one direction. Connected with each pin 52 is a spring 54 for normally holding the 70 pin in engagement with its corresponding stop.

Mounted for limited vertical sliding movement in the block 44 in a suitable slot 55 therein, is a bar 56 having downwardly projecting pins 57 extending into coil springs 58, on which the bar 56 rests. The bar 56 is arranged transversely with relation to the slide bars.

Slidably mounted above the bar 56 is 80 a bar 59, which for convenience I have called the locking bar. In the upper surface of the locking bar 59 are notches 60, which, when the parts are in normal position, stand below the respective slide bars 85 and receive said slide bars.

Suitably mounted for sliding reciprocating movement, forwardly of the block 44, is a rack bar 61 having teeth 62 which mesh with the teeth of a pinion 63 on a 90 shaft 64 suitably mounted in the frame members 65 and 66 in the casing 14.

Mounted preferably on the upper surface of the rack bar 61 are the cam blocks 67, 68, 69 and 70, which normally stand 95 adjacent to the lower ends of the respective pivoted pins 52. The cam blocks are so arranged that when the slide bars are slid rearwardly in the machine, the pins 52 will engage said cam blocks for forcing the rack 100 bar 61 laterally for imparting limited rotation to the pinion 63 and the shaft 64.

It may be mentioned in this connection that on the return movement of the respective slide bars the pins 52 may swing 105 on their pivot points against the tension of the springs 54 for allowing the pins to clear the cam blocks.

Suitably mounted parallel with the shaft 64 is a shaft 71 on which is a gear 72 110 which meshes with a gear 73 on the shaft 64.

Mounted for vertical sliding movement in the machine is a toothed bar 12, arranged between the shafts 64 and 71, as illustrated in Figs. 2 and 3. The bar 12 has teeth 74 115 and 75 on its opposite sides, adjacent to the respective shafts 71 and 64.

On the shaft 64 is fixed a disk 76. Adjacent to the disk 76 a disk 77 is rotatably mounted on the shaft 64. The disks 76 and 77 are connected by a coil spring 78. On the disk 77 is a pawl 79, designed in one position of the disk 77 to coact with the teeth 75 of the bar 12 for preventing downward movement of said bar. The normal 125 position of the pawl 79 is extending upwardly and away from the bar 12, as illustrated by dotted lines in Fig. 2.

In the disk 76 is a curved slot 80, which receives a pin 81 extending from the disk 130

77, for permitting limited rotation of the disks 76 and 77 with relation to each other. The spring 78 is so arranged as to tend to hold the disk 77 in such position of its rotation with relation to the disk 76, as to hold the pawl 79 as near to the bar 12 as possible.

On the shaft 71 is a similarly constructed pawl device designed to coact with the teeth 74 on the other side of the bar 12. On the shaft 71 is fixed a disk 82. Adjacent to the disk 82 there is loosely mounted on the shaft 71 a disk 83, on which is the pawl 84 extending downwardly. The disks 82 and 83 are connected by a spring 85 similar to the spring 78.

In the disk 82 is a curved slot 86, which receives the pin 87^a on the disk 83 for thereby limiting the rotary movement of the disk 83 with relation to the disk 82. The spring 85 is so arranged as to tend to hold the pawl 84 at the limit of its movement toward the bar 12 with relation to the disk 82. The locking bar 59 has near its end a pin 88 received in an elongated slot 89 in an arm 90 on the shaft 71. (See Figs. 2, 4 and 10.)

Mounted in suitable bearings for vertical reciprocation in the casing 14, is a measuring bar 91 having thereon the graduations 92. The upper end of the bar 91 has a reduced cylindrical portion 93 slidably received in a suitable bearing. The upper end of the main portion of the bar 91 adjacent to the portion 93 forms a shoulder 94. It will be seen that the bar 91 may be pushed upwardly a short distance from its normal lower position, and that its upward movement is limited by the shoulder 94.

Adjustably mounted on the bar 91 and projecting in different directions from said bar are stop arms 95, 96, 97 and 98, which may be secured in any of the different positions of their vertical adjustment by means of set screws 99. On the upper end of the bar 12 is a suitable head 100, normally standing below the level of the lowermost stop bar 95. The bar 91 is mounted for rotation as well as for vertical sliding movement.

Fixed on the bar 91 is a wide gear 101, which meshes with a segmental gear 102 mounted on the vertical stub shaft 103. The segmental gear 102 has an arm 104 projecting therefrom into the paths of movement of the rear ends of the slide bars 45, 46, and 47, as illustrated in Fig. 3.

Pivoted on a bracket 105 is an arm 106, one end of which stands above the gear 101. Pivoted to the other end of the arm 106 is a downwardly hanging arm 107. On the shaft 71 is an arm 108, which projects to position below the arm 107, as shown in Figs. 3 and 4. A spring 109 tends to draw the arm 104 toward the slide bars 45, 46 and 47, as shown in Fig. 3.

65 I will now describe the practical opera-

tion of my improved coin operated mechanism for gasoline vending machines and other such devices.

Of course it will be understood that the bar 12 is connected with the crank handle 13 in a suitable manner, and also with a suitable pump which discharges through the flexible tube 110, or otherwise, as may be desired.

The stop arms 95, 96, 97 and 98 are adjusted at the proper heights on the graduated bar 91. Normally the springs 37 hold the plunger rods 34 in their forward positions of movement, the springs 42 hold the slide bars in their forward positions, the spring 109 holds the segmental gear 102, the gear 101 and the bar 91 in such positions that the upper stop bar 98 stands directly above the head 100 on the toothed bar 12. The shafts 64 and 71 stand in the positions shown in Fig. 4, with the pawl 84 engaging the teeth 74, and the pawl 79 free from the teeth 75.

Assuming that a coin, such, for instance, as a half dollar, is dropped into the slot 17, it will then slide downwardly through the proper chute 19 until stopped by the contracted portion 20. This contracted portion will stop the coin exactly in line with the proper cylinder 39. In the forward wall 95 of each chute 19 is a suitable hole 111 to admit the corresponding plunger rod 34. After the coin has been dropped into the machine, the crank 30 may then be operated for swinging the arm 31 for actuating the bar 33 and the plunger rods 34. The disks 41 and cylinders 40 have openings 112 to permit the inoperative entrance of the plunger rods 34 where no coin has been deposited.

When the crank handle 30 is operated after the half dollar has been deposited, the proper plunger rod 34 will engage the coin, forcing it into the cylinder 39 and forcing the disk 41 and the rod 40 and the corresponding slide bar 47 against the tension of the spring 42 rearwardly in the machine. The slide bar 47 in its rearward movement, of course, carries with it the catch pin 52 which engages the cam block 69 for forcing the bar 61 laterally toward the left. The same movement of the slide bar 47 causes the arm 104 and the segmental gear 102 to swing on the shaft 103 for imparting such rotation to the gear 101 and the bar 91 as to bring the stop bar 97, which is the half dollar stop bar, to position projecting above the head 100. The leftward sliding movement of the bar 61 imparts limited rotation to the gear 63 and the shaft 64. Such rotation is imparted to the disk 76, and through the pin 81 to the disk 77, for bringing the pawl 79 into engagement with the teeth 75 on the bar 12. The rotation of the shaft 64 imparts rotation to the gears 73 and 72, and from thence to the 130

shaft 71 and the disk 82 mounted thereon. The first part of such rotation moves the disk 82 from position with the pin 87 as shown in Fig. 4, to position where the pin is in the other end of the slot 86, and during the latter part of the rotation of the shaft 71 and disk 82 the disk 83 is moved for withdrawing the pawl 84 from engagement with the teeth 74.

10 It will be noted that on account of the peculiar connection of the disks 82 and 83, the pawl 84 is not moved out of engagement with the teeth of the bar 12 until the latter part of the operation of the machine, whereupon the bar 12 may be moved upwardly by the movement of the crank 13, or otherwise, for delivering gasolene from the machine.

15 In the meanwhile, the machine has been locked against the return of the parts to their normal position, in the following manner:

20 Before starting the operation, the bar 47 stood in the position shown in Fig. 14, with relation to the locking bar 59, with the rearward end of the slot 50 above the corresponding slot 60 in the bar 59. The rearward sliding movement of the bar 47 carries it in the direction indicated by the arrow in Fig. 14, to position where the slot 49 is 25 above the locking bar 59, as illustrated in Fig. 13. During the rearward sliding movement of the bar 47 the rotation of the shaft 71 and the consequent movement of the arm 90 impart lateral sliding movement to the 30 right to the locking bar 59, for moving the slots 60 out of register with the respective slide bars. The movement of the slide bar 47 depresses the locking bar 59 until the 35 notch 49 in the slide bar 47 comes to position directly above the locking bar, whereupon the springs 58 force the locking bar 59 upwardly into the notch 49 of said slide bar 47, whereupon the slide bar 47 is held against the tension of the spring 42 from returning 40 to its original starting position. The operation of the crank 13 serves, by mechanism which is not here shown, but which is of ordinary construction in common use, to raise the toothed bar 12. The crank 13 may 45 be operated for so raising the toothed bar 12 until the head 100 on said bar engages the stop bar 97. Thereafter there may be sufficient further operation of the mechanism to raise the bar 91 until the shoulder 94 engages the bearing for the portion 93, whereby the upward movement of the bar 91 and bar 12 are finally limited.

50 The short upward sliding movement of the bar 91 carries upwardly the gear 101, which, in such upward movement, raises the end of the arm 106 adjacent to said gear and correspondingly lowers the opposite end of said arm. The arm 108 by the first part of the operation of the machine is raised upwardly until it stands adjacent to the arm

5 107. The upward movement of the gear 101 lowers the arm 107, thereby forcing downwardly the arm 108 and imparting rotation to the shaft 71 in a direction opposite that of its first rotation, returning the shaft 71 to 70 its original position and moving the pawl 84 into engagement with the teeth 74. The rotation of the shaft 71 moves the arm 90 for returning the locking bar 59 to its original position where the notches 60 register with 75 the locking bars, whereupon the spring 109 returns the segment 102 and the bar 91 to their original positions, and forces the slide bar 47 forwardly in the machine for returning said parts to their original starting position. The rotation of the shaft 71, through the gears 72 and 73, returns the shaft 64 to its original position, thereby throwing the pawl 79 out of engagement with the teeth 75.

80 In this connection it will be noted that the frictional engagement of the pawl 79 with the teeth 75 will prevent the disengagement of the pawl 79 and teeth 75 until the disk 76 has moved a sufficient distance to permit the pin 81 to travel from one end to the other of the slot 80 so that the pawl is not disengaged until the latter part of the operation of the machine during the returning of the parts to starting position. The operation of the shaft 64, now being described, returns the bar 61 to its original position.

85 On account of the swinging mounting of the pin 52 on the bar 47, said pin may swing upwardly against the tension of the 90 spring 54 for permitting it to clear the cam block 69, but as soon as such clearing is completed the spring 54 returns the pin 52 to its downwardly hanging position. The spring 42 assists in returning the slide bar 105 47 to its original position after the locking bar 59 has slid to position for permitting the return of the slide bar. During the return of the slide bar the coin drops through the chute 43 upon the swinging hinged bottom 110 25, and there remains in plain sight until the next operation of the machine.

Upon the next operation of the machine the partial rotation of the shaft 29 through the means of the crank 30, actuates the arm 115 28 and the arm 27 for tilting the bottom 25 and dropping the coin thereon downwardly.

The operation of the machine after the deposit of other coins is similar to that already described.

120 Where the largest coin is deposited, there is no operation of the segmental gear 102, for the reason that the slide bar 48 clears the end of the arm 104. Hence there is no rotation of the bar 91. It will thus be seen 125 why the stop arm 98, by which the amount of gasolene delivered for the coin is determined, is arranged directly above the head 100.

130 For smaller coins the operation is similar

to that described, with the exception that the slide bars move the arm 104 different distances for thereby imparting different degrees of rotation to the bar 91 for bringing 5 the proper stop arms 95 and 96 above the head 100.

The advantages of a mechanism of the kind herein described may be largely seen from the foregoing description of its construction and operation.

If the user deposits too small a coin in the half dollar slot, for instance, the coin will simply drop through and be delivered into the cup member 22^a and returned to the 10 owner. On account of the arrangement of the locking bar, there can be no operation of the machine but such as to deliver the complete amount of gasoline or the like paid for, until another coin has been deposited. Only the complete operation of 15 the machine for delivering the proper amount of the vended commodity will serve to unlock the machine for another operation. The peculiar arrangement of the pawls is 20 such as to keep the bar 12 locked except for one complete operation for each coin.

It will be readily seen that by very simple modification the machine may be changed for use with any desired coins. 30 The amount of the commodity to be delivered for any particular coin may be readily regulated by the adjustment of the stop arms 95, 96, 97 and 98, which can readily be adjusted on the bar 91 by means of 35 the set screw 99.

I have shown the rear portion of the casing 14 provided with a hinged door 14^a for permitting ready access to the mechanism within the casing.

40 Changes may be made in the construction and arrangement of the various parts of my improved coin operated mechanism, without departing from the real spirit and purpose of my invention, and it is my intention 45 to cover by my claims any modified forms of structure or use of mechanical equivalents which may be reasonably included within their scope.

I claim as my invention:

50 1. In a machine of the class described, a casing, a coin chute therein having a portion adapted to receive and hold a coin, a cylinder extender from said portion, a rod in said cylinder, a slide bar connected with 55 said rod, a plunger adapted to engage a coin in said portion for forcing the coin into said cylinder and actuating said slide bar, a locking bar, said slide bar and locking bar having portions adapted to engage when 60 the said bars are in certain positions of their movement, for holding the slide bar against movement in one direction, means tending to yieldingly move the slide bar in another direction, an actuating bar, devices for 65 locking said actuating bar against sliding

movement in either direction, means for actuating one of said devices from said slide bar, a member slidably and rotatably mounted, adjustable means thereon for limiting the movement of said actuating bar, 70 means for limiting the sliding movement of said member, and means adapted to be actuated by the movement of said member for moving the locking bar to inoperative position. 75

2. In a machine of the class described, a casing, a coin chute therein having a portion adapted to receive and hold a coin, a cylinder extending from said portion, a rod in said cylinder, a slide bar connected with 80 said rod, a plunger adapted to engage a coin in said portion for forcing the coin into said cylinder and actuating said slide bar, a locking bar, said slide bar and locking bar having portions adapted to engage when 85 the said bars are in certain positions of their movement, for holding the slide bar against movement in one direction, means tending to yieldingly move the slide bar in another direction, an actuating bar, devices for locking 90 said actuating bar against sliding movement in either direction, means for actuating one of said devices from said slide bar, a member slidably and rotatably mounted, adjustable means thereon for limiting the 95 movement of said actuating bar, means for limiting the sliding movement of said member, and means adapted to be actuated by the movement of said member for moving the locking bar to inoperative position and for 100 moving the other of said devices to locking position.

3. In a device of the class described, a slide bar, means for actuating said slide bar through the medium of a coin, an actuating bar, means for locking said actuating bar against movement in one direction, means operable from said slide bar for releasing said locking means, and a locking bar arranged to be moved to operative position 105 when said slide bar is operated, a member having a stop device thereon, said member being capable of limited sliding movement, and a device capable of being operated upon the sliding movement of said member, for 110 moving said locking bar to unlocking position.

4. In a device of the class described, a casing, a series of slide bars mounted therein, means for actuating said slide bars 120 through the medium of coins, a locking bar, means for moving said locking bar to operative position when any one of the slide bars is actuated, an actuating bar, locking means arranged to be operated by a movement of 125 the slide bar for movement to inoperative position with relation to said actuating bar, a member rotatably and slidably mounted, having stop devices thereon, means whereby the movement of the slide bar actuates 130

said member for bringing one of said stop devices to a definite position with relation to said actuating bar, and means arranged to be actuated by the movement of said member, for returning said second means to its starting position.

5. In a device of the class described, a casing, a series of slide bars mounted therein, means for actuating said slide bars through the medium of coins, a locking bar, means for moving said locking bar to operative position when any one of the slide bars is actuated, an actuating bar, locking means arranged to be operated by a movement of the slide bar for movement to inoperative position with relation to said actuating bar, a member rotatably and slidably mounted, having stop devices thereon, means whereby the movement of the slide bar actuates said member for bringing one of said stop devices to a definite position with relation to said actuating bar, and means arranged to be actuated by the movement of said member, for returning said second means to its starting position, said second means including a locking member designed to coact with said locking bar and to be moved to operative position when said first locking device is moved to inoperative position.

6. In a device of the class described, a series of slide bars, means for actuating said slide bars through the medium of coins, an actuating bar, locking devices for holding said actuating bar against movement in opposite directions, means arranged to be actuated by movement of any one of said slide bars for moving one of said locking devices out of operative position and for moving the other of said locking devices into operative position, an adjustable member for limiting the movement of said actuating device, and means actuated by the movement of said adjustable member, for returning said last means to normal position.

7. In a device of the class described, a series of slide bars, means for actuating said slide bars through the medium of coins, a movable actuating bar, locking devices for respectively holding said actuating bar against movement in opposite directions, means selectively operable from either of said slide bars for moving one of said locking devices out of engagement and the other into engagement with said actuating bar, a bar mounted for rotation and for limited sliding movement, having stop devices thereon for coacting with said actuating bar, and means arranged to be actuated from said last bar, for reversing the movement of said locking devices.

8. In a device of the class described, a series of slide bars, means for actuating said slide bars through the medium of coins, a movable actuating bar, locking devices for

respectively holding said actuating bar against movement in opposite directions, means selectively operable from either of said slide bars for moving one of said locking devices out of engagement and the other into engagement with said actuating bar, a bar mounted for rotation and for limited sliding movement, having stop devices thereon for coacting with said actuating bar, and means arranged to be actuated from said last bar, for reversing the movement of said locking devices, said stop devices being adjustable.

9. In a device of the class described, a series of slide bars, means for actuating said slide bars through the medium of coins, a movable actuating bar, locking devices for respectively holding said actuating bar against movement in opposite directions, means selectively operable from either of said slide bars for moving one of said locking devices out of engagement and the other into engagement with said actuating bar, a bar mounted for rotation and for limited sliding movement, having stop devices thereon for coacting with said actuating bar, means arranged to be actuated from said last bar, for reversing the movement of said locking devices, and means adapted to be selectively operated by said slide bars for moving said last bar to bring the stops thereon selectively to position for co-operating with said actuating bar.

10. In a device of the class described, a series of slide bars, means for actuating said slide bars through the medium of coins, a movable actuating bar, a measuring bar mounted for rotation, stop devices thereon projecting in different directions therefrom, and means adapted to be operated by the respective slide bars for rotating said measuring bar for selectively bringing the different stops thereon into the path of movement of said actuating bar.

11. In a device of the class described, a series of slide bars, means for actuating said slide bars through the medium of coins, a movable actuating bar, locking devices for respectively holding said actuating bar against movement in opposite directions, means selectively operable from either of said slide bars for moving one of said locking devices out of engagement and the other into engagement with said actuating bar, a bar mounted for rotation and for limited sliding movement, having stop devices thereon for coacting with said actuating bar, means arranged to be actuated from said last bar, for reversing the movement of said locking devices, and means adapted to be selectively operated by said slide bars for moving said last bar to bring the stops thereon selectively to position for co-operating with said actuating bar, said stop devices being adjustable.

12. In a device of the class described, a movable actuating bar, an adjustable measuring bar, stops thereon, and a series of devices arranged to be selectively actuated through the media of coins, for selectively bringing different stop devices into the path of movement of said actuating bar, said actuating devices including slide bars, means for automatically locking the actuated slide

bar against return movement when it is operated, means tending to return the slide bars to their normal positions, and means arranged to be actuated by the movement of said measuring bar for releasing said locking means. 10
